Patented Dec. 19, 1972

225,489

KNIT DRESS OR THE LIKE

Margaret A. Graham, Rte. 2, P.O. Box 111,
Cary, N.C. 27511

Filed Apr. 27, 1970, Ser. No. 22,660

Term of patent 14 years

Int. Cl. D2—02

U.S. Cl. D2—43

Fig 1

Fig 4

FIG. 1 is a front elevational view of a knit dress or the like showing my new design;

FIG. 2 is a rear elevational view thereof;

FIG. 3 is a front elevational view of the knit dress with the sleeve tuck shown turned up; and

FIG. 4 is a rear elevational view of the same.

The dark background shown in the figures is for the purposes of illustration.

I claim:

The ornamental design for a knit dress or the like, as shown and described.
